United States Patent [19]

Finch

[11] Des. 250,865
[45]  Jan. 23, 1979

[54] BAR OR SIMILAR ARTICLE

[76] Inventor: Lloyd J. Finch, 427 Fillmore St., San Francisco, Calif. 94117

[] Term: 14 Years

[21] Appl. No.: 905,929

[22] Filed: May 15, 1978

D. 228,103 8/1973 Skalka et al. .... D6/144 X
D. 228,482 10/1973 Flemings D6/144
3,672,741 6/1972 Clark ..... D6/144 X

Primary Examiner—Bruce W. Dunkins
Attorney, Agent, or Firm—Stephen S. Townsend

[57] CLAIM

The ornamental design for a bar or similar article, as shown and described.

DESCRIPTION

FIG. 1 is a top front perspective view of a bar or similar article showing my new design;

FIG. 2 is a fragmentary perspective view, partially cutaway, showing the simulated waterfall display embedded in the front thereof;

FIG. 3 is a bottom rear perspective view thereof;

FIG. 4 is a top plan view thereof;

FIG. 5 is a front elevation view thereof;

FIG. 6 is a left side elevation view thereof, the right side elevation view thereof being a mirror image;

FIG. 7 is a bottom view thereof; and

FIG. 8 is a rear elevation view thereof.
